UNITED STATES PATENT OFFICE.

EMMONS OVERMIER, OF LA GRANGE, ILLINOIS, ASSIGNOR TO MAINTENANCE EQUIPMENT COMPANY, OF CHICAGO, ILLINOIS, A CORPORATION OF ILLINOIS.

BALLAST-REMOVING MACHINE.

Application filed August 5, 1926. Serial No. 127,352

This invention relates to a ballast removing machine, and especially to a machine for removing material from between the ties of a railway track. More particularly, the 5 invention relates to a self-contained, portable apparatus, movable along the track for performing this ballast removing operation. A machine of this type is disclosed and claimed in my copending application, Serial No. 747-10 537, filed November 3, 1924, now Patent No. 1,588,801, dated June 15, 1926, and this present invention relates to improvements in the machine disclosed and claimed in said copending application.

15 The principal object of the present invention is to provide certain improvements in a machine of the type briefly referred to hereinabove, and described more in detail in the specification which follows.

20 Another object is to provide a machine of this type with means whereby it may be bodily raised or lowered with respect to the supporting wheels. Certain portions of the apparatus are normally below the level of 25 the tracks on which the machine is supported when in operating position, and by the use of this means all portions of the apparatus may be raised clear of the tracks so that the machine can be transported for any distance.

30 Another object is to provide improved lifting-jack means for elevating the apparatus with respect to the supporting wheels.

Another object is to provide an apparatus of this type with two sets of supporting 35 wheels, arranged at right angles to one another, in combination with means whereby the entire weight of the machine can be transferred from one set of supporting wheels to the other.

40 Another object is to provide power-driven means for operating the raising and lowering mechanism, said means being provided with an automatic stop device operative when the apparatus has reached the upper or lower 45 limits of its travel.

Another object is to provide an apparatus of this type, which embodies diggers operative beneath the track rails and between the ties, with means for automatically guiding the 50 diggers into the spaces beneath the rails as the diggers are lowered, and for moving them out from under the rails as they are elevated.

The above and numerous other objects and advantages of this invention will be apparent 55 from the following detailed description of

one approved form of the apparatus, involving the principles of this invention.

In the accompanying drawings:

Fig. 1 is a side elevation of the complete machine, in position on the track rails. 60

Fig. 2 is an end view of the machine, the supporting rails being shown in transverse vertical section. The diggers are shown in lowered position, operating between a pair of ties. 65

Fig. 3 is a detailed view similar to the right hand end of Fig. 2, showing, on a somewhat larger scale, the outer digger in a raised position.

Fig. 4 is a horizontal section, taken substantially on the line 4—4 of Fig. 3. 70

Fig. 5 is a perspective view of the lower portion of the guiding member or bracket.

Fig. 6 is a central vertical section through one of the lifting jacks, which supports the 75 apparatus from the car wheels.

Fig. 7 is an enlarged side elevation of the clutches and stop mechanism for controlling the lifting jacks.

Fig. 8 is an end view of this mechanism, 80 the view being taken substantially on the line 8—8 of Fig. 7.

The car or supporting frame 1 which carries all of the apparatus hereinafter described, is mounted on wheels 2, adapted to 85 travel on the rails 3 supported in the usual manner on ties 4. The frame 1 and the apparatus carried thereby are supported from the wheels 2 through suitable raising and lowering mechanism which will be described in detail hereinafter. During the 90 normal operation of the digging mechanism, this raising and lowering mechanism is not used. The platform 5 at one end of the car supports the engine of power plant 6 for 95 driving the car and the digging mechanism. This engine may be of any suitable type, but is preferably an internal combustion engine as indicated. The car is preferably hauled from place to place by attaching same 100 in the usual manner to a train or locomotive, although gearing connections (not here shown), may be provided whereby the car can drive itself from the power plant 6. Such connections are disclosed in my copending application Serial No. 747,537, hereinabove referred to. 105

The forward portion of frame 1 comprises base portions 7, and a superstructure 8, built up of suitable metal beams, in which the dig- 110

ging mechanism is mounted. This digging apparatus consists of two separate substantially identical units, each one operating to excavate one-half of the roadway, that is, 5 from the center line of the trackway to one end of the ties. A driving crank 9 for one of these units is mounted at one side of the supporting frame, and a similar driving crank 10 is mounted near the opposite side 10 of the supporting frame, these cranks being normally driven in opposite directions, as indicated by the arrows in Fig. 2. A driving shaft 11, mounted longitudinally through the superstructure 8, is driven from 15 the power plant or engine 6, through sprocket gearing indicated at 12, and a clutch 13 controlled by lever 14 is provided whereby the power may be thrown on or off as desired. A sprocket chain 15 connects a small 20 sprocket 16 on one end of drive shaft 11, with a larger sprocket 17 mounted on the axis 18 of the crank 9, the sprocket 17 and crank 9 forming substantially a unit rotatable about the axis 18. Crank 10 is driven 25 in a similar manner but in the opposite direction by a sprocket chain 19, the upper end of which is driven by a small sprocket 20, which in turn is driven through a pair 30 of similar intermeshing spur gears 21 from the drive shaft 11. The crank 9 operates one digging unit, that is, the mechanism for excavating one-half of the roadbed, and the crank 10 drives the other unit in an exactly similar manner. Since these two units, that 35 is the two halves of the machine, are substantially identical, only one of them need be described in detail, and we will describe the unit shown at the right-hand half of Fig. 2, that is, the unit driven from crank 9.

40 Each excavating unit comprises an outer digger 22, adapted to remove the material from between the end portions of the pair of adjacent ties 4, and from beneath the rail 3, and an inner digger 23 adapted to remove 45 the material from the center line of the track, or slightly beyond this center line, out to the rail 3. Each digger 22 or 23 comprises a plurality of scoops or spades 24, which are adapted to move in looped or elliptical paths, as indicated in dotted lines in 50 Fig. 3, so as to first dig down into the ballast, then move outwardly substantially horizontally to throw the material toward the side of the track, then move up and back 55 over their former paths to repeat the operation. The cribs or spaces between adjacent ties 4 vary considerably in width in the ordinary roadbed, and the spades 24 are preferably made sufficiently narrow to operate in 60 practically any of these cribs.

The outer digger 22 is mounted to slide in a direction perpendicular to rails 3, that is, longitudinally of the ties 4, upon guide rods or sideways 25, in the auxiliary carriage or 65 supporting frame 26. The reason for this

sliding movement of digger 22 on rods 25 will be explained hereinafter, but for the present we may consider the digger 22 as substantially fixed with relation to the supporting carriage 26. 70

A pair of bellcranks 27 are intermediately secured near opposite ends of a cross-shaft 28, mounted in bearings 29 on the upper portion of superstructure 8. A similar pair of bellcranks 30 are mounted on a cross-shaft 75 31 which is parallel to shaft 28 and spaced inwardly therefrom. The shorter arms 32 of the respective bellcranks 27 and 30 at the same side of the machine, are connected by links 33, so that all four of the bellcranks will swing in unison. A downwardly extending crank arm 34 secured to one end of shaft 31 is formed with a slot 35 in which engages a pin 36 on nut 37 adapted to travel lengthwise of the threaded shaft 38 mounted in suitable bearings 39 in the superstructure 80 and extending transversely of the car. 85

In an exactly similar manner, two other sets of bellcranks 40 and 41 are mounted inwardly of the supporting frame on shafts 42 and 43 parallel with the shafts 28 and 31, previously described. The shorter arms of the bellcranks 40 and 41 are connected by the links 44. A crank arm 45 secured to one end of shaft 42 has a slot 46 in which engages a pin 47 on the nut 48 threaded on screw shaft 49, which is mounted in the frame similarly to shaft 38 but at the opposite end of the machine. 90

A shaft 50 is mounted in the upper central portion of the machine, and extending longitudinally of the car, and is driven through sprocket chain connections 51 and 52, from the engine 6. A worm wheel 53 on screw shaft 49 meshes with a worm wheel 54 rotatable on the drive shaft 50. Worm wheel 54 may be clutched to the shaft 50 by means of the sliding clutch member 55 controlled by lever 56. In an exactly similar manner, the screw shaft 38 is driven from shaft 50 through the worm gearings 57, and clutch member 58 controlled by the lever 59. A rod connection 60 extends longitudinally of the machine and is connected with the lever 56 whereby the clutches 55 and 58 may be selectively manipulated from the same point on the machine. 100

A supporting frame comprises a pair of downwardly hanging links 61, which are pivoted at their upper ends 62 to the ends of the longer arms of the bellcranks 27. An exactly similar pair of links 63 are similarly suspended from the bellcranks 30. In the same manner, supporting links 64 and 65 are suspended from the bellcranks 105 110 115 120 125 40 and 41.

A casting or frame 66 comprises parallel side bars 67, which are pivoted at their ends 68 to the ears 69 extending upwardly from the side members of carriage 26 near one 130

end thereof. The other ends of side bars 67 are pivoted on a transverse shaft 70, which is suspended in the lower ends 71 of the links 63. A pair of levers 72 intermediately pivoted at 73 to the central portions of the side bars 67 are pivoted at their upper outer ends 74 to the lower ends of the links 61, and are pivoted at their inner lower ends to the short links 75, which in turn are connected to the carriage 26. A pitman or connecting rod 76 is connected at one end to an extension 66' of the frame 66, and is pivoted at its other end on the crank pin 77 of the driving crank 9. It will be noted that as the crank 9 is rotated continuously in the direction of the arrow, Fig. 2, the pitman 76 will be reciprocated back and forth lengthwise of the ties 4, and will also swing intermediately about the pivotal connections with the lower ends 71 of links 63, so that the outer ends 68 of the pitman will rise and fall, raising and lowering the carriage 26 as it is swung backwardly and forwardly. The members 67 and 72 constitute a lazy tongs, alternately expanding and contracting to lower and raise the digger as it is oscillated. This will cause the carriage 26, and consequently the digger 22 suspended therefrom, to move through a looped or elliptical path, as indicated in dotted lines in Fig. 3. The function of the second pair of links 61, and the levers 72, is to impart a similar parallel motion to the other end of carriage 26, the carriage remaining substantially parallel with the ground at all times. The short links 75 are to compensate for the varying distances between the lower ends of levers 67 and 72 as the carriage is raised and lowered by the swinging movement of the operating pitman 76.

A quite similar mechanism is provided for suspending and operating the inner digger 23. A second pitman 78, similar in construction to the pitman 76, but shorter, is pivoted at one end on the crank pin 77. The other forked end portion of this pitman is intermediately pivoted at 79 to the lower ends of the links 65, and the ends 80 of the pitman are pivoted at 81 to the ears 82 on the digger 23. The forked end portions 80 of the pitman are intermediately pivoted at 83 to levers 84, suspended at one end 85 from the links 64, and at the other ends connected through short links 86 with ears 87 on digger 23. The general construction and operation of this supporting mechanism for the inner digger 23 is the same as that described in more detail for the outer digger 22, and it will be noted that the inner and outer diggers 23 and 22 are simultaneously operated through their respective paths by the same crank 9.

The inner digger 23 is adapted to excavate the ballast material in the space between the center line of the roadbed, and

the inner face of the rail 3. Its operating path is approximately the same when raised as when lowered. On the contrary, the outer digger 22 when in elevated position, is adapted to operate only in the space between the ends of the ties beyond the rail 3, but when lowered it is adapted to operate beneath the rail 3 as well as in the space between the ends of the ties 4. It is for this reason that the digger 22 is mounted for longitudinal sliding movement on the rods 25 in the auxiliary carriage 26, and one feature of the present invention is to provide improved means for automatically sliding the digger 22 along these rods 25 as the digger is raised or lowered. A swinging plate or member 88 is pivotally suspended at its upper end on a cross shaft 89 carried by lever arms 27' which extend rearwardly from and in line with the longer arms of bell-cranks 27. At the lower end of plate 88 is attached a cam structure 90, best shown in Fig. 5. This cam plate embodies an inner cam slot 91 and an outer cam slot 92, the upper portions of these slots being substantially parallel with one another. The lower portion 93 of slot 92 inclines sharply inwardly until it terminates substantially in line with the upper portion of slot 91, if extended downwardly. On the other hand, the lower portion 94 of inner slot 91 inclines sharply outwardly until it terminates against the wall of slot 93 as indicated at 95. The cross shaft 70, which forms the pivotal connection between forks 67 of frame member 66, and the lower ends of links 63, is adapted to slide vertically in the slot 91 as the supports for digger 22 are raised or lowered. A bracket 96 extending upwardly from the digger 22, carries a pin 97 engaging in the slot 92.

The outer and inner diggers 98 and 99 at the left-hand side of the apparatus as seen in Fig. 2, are exactly similar to the diggers 22 and 23 previously described, and are suspended and operated in the same manner. The pitmen 100 and 101 for these diggers 98 and 99, are connected with and operated from the crank pin 102 of the other operating crank 10. It will be noted from Fig. 2 that there is substantially 90° difference in the relative angular positions of the cranks 9 and 10 on their respective shafts. This is to give a slightly different timing to the two sets of diggers, so that the inner diggers 23 and 99 will not both reach the inner limit of their travel at the same time. In this way, each of these diggers can slightly overlap the center line of the track without interfering with one another. This insures the complete removal of all of the material lying between the ties. The cranks 9 and 10 might be positioned at other relative angles, such as 180°, to accomplish the same result.

In operation, we will assume that the engine 6 is operating, and that the car has been properly located above one of the spaces between a pair of adjacent ties 4, and that 5 all of the diggers are in their extreme elevated positions. By throwing in clutch 13 by means of lever 14, the several diggers are now thrown into gear and these diggers will commence to travel through their elliptical 10 orbits, without, however, coming in contact with the ballast between the ties, since the diggers are now at their extreme upper adjustments, so as not to contact with the material to be excavated. By means of lever 15, clutch 58 is now thrown into gear, thus causing screw shaft 38 to be rotated. This will gradually move inwardly, that is, toward the center of the machine, the nuts 37 on the oppositely threaded ends of shaft 20 38, thus causing the simultaneous lowering of all of the outer longer arms of the bellcranks 27 and 30, whereby the supporting carriages 26 and the outer diggers 22 will be gradually lowered. As these diggers are 25 lowered, they continue to oscillate through their elliptical orbits, so that the material between the outer ends of ties 4 will be dug out and thrown beyond the outer side of the trackway. As the upper paths of the orbits 30 of the diggers 22 reach approximately the level of the lower surfaces of rails 3, the pins 70 and 97 will enter the lower inclined ends 94 and 93 of the cam slots 91 and 92, since the swinging bracket or guide plate 35 does not move downwardly with the diggers, but, on the contrary, moves upwardly at this time since it is suspended from the oppositely projecting arms 27' of bellcranks 27. As the downward movement of the digger 40 continues, the pin 97 will be forced inwardly along the inwardly inclined slot 93, thus sliding the digger 22 inwardly along the guide rods 25. At the same time, the shaft 70 will pass into the lower outwardly inclined slot 94, thus forcing the plate 88 carrying the cam plate 90 to swing inwardly, thus also through pin 97 and bracket 96, sliding the digger 22 inwardly along guide rods 25. It will be noted that the effect of 45 the two oppositely inclined slots 93 and 94 is accumulative, each tending to shift the digger 22 inwardly, so that a rapid adjustment of the digger 22 toward the inner ends of the guide rods 25 is accomplished. The 50 rapidity of this shifting movement is again substantially doubled due to the fact that the cam plate 90 is moving up as the digger moves down, thus accelerating the passage of the shafts 70 and pin 97 through cam slots 94 and 93. In this way, the orbits of 55 the outer diggers 22 will be very quickly moved back beneath the rails 3 to remove the ballast or other material from beneath the rails. When this excavating operation is completed, the lowering of the outer diggers 60 65 22 is discontinued by throwing out the clutch 58. The clutch 55 is now thrown into gear, thus rotating the screw shaft 49 and causing the inner diggers 23 and 99 to be lowered in substantially the same manner as 70 already described for the outer diggers, with the exception that no means is provided to move these inner diggers under the rails. The material within the crib or space between the ties from the center line of the 75 track to the rails 3 is now dug up by these inner diggers and thrown into the excavation previously made by the outer diggers 22 and 98. The outer diggers, which are still in operation, will throw this material 80 on beyond the ends of the cars. When the excavation of a crib has been completed, the direction of rotation of drive shaft 50 is reversed (by means of reversing mechanism located at the engine 6 and not 85 here shown), and all of the diggers are quickly elevated by throwing in both clutches 55 and 58. The raising and lowering mechanism for the several diggers as hereinabove described, is capable of raising the digging mechanism clear of the roadbed and ties 4, but they will not be raised completely above the level of the rails 3, so that the machine 90 cannot be safely transported for any distance along the tracks, particularly across switches or track crossings, without raising the mechanism until it is entirely clear of the tracks. To accomplish this, and also to 95 permit the digging mechanism as an entirety to be adjusted vertically to meet different conditions of operation, lifting mechanism is provided between the main supporting frame 1 and the car wheels 2, whereby the 100 entire apparatus supported by these wheels 105 can be raised as a unit. The respective pairs of wheels 2 at the front and rear ends of the car are mounted on the ends of cross axles 103 in the usual manner. The respective ends of these axles 103 are supported in 110 bearings or journal boxes 104, see Fig. 6. Secured to or integral with the bearings 104 are upstanding posts 105, each fitting within and adapted for vertical sliding movement 115 in a guide or socket 106, one of which is rigidly built into each corner of the car frame 1. The post 105 and socket opening in guide 106, may be circular or square, or of any other desired configuration in cross section, it only being essential that the post 105 be rigidly sustained within the guide 106, but capable of vertical sliding movement therein. A nut 107, formed of bronze or other suitable metal, is screwed or otherwise secured in the upper end of post 105, and an operating screw 108 is threaded within nut 107, the lower portion of this screw being freely housed within the hollow lower portion 109 of the post 105. The rotatable screw 108 supports the weight of the 120 125 130

supporting frame 1 and parts carried thereby, by means of a thrust collar 110, bearing against the lower face of head 111 of guide member 106. A beveled gear 112, and a worm wheel 113, are keyed on the upper end of screw 108 above the head 111, and held in place by a lock nut 114. A cross-shaft 115, mounted in bearings 116, in supporting frame 1, has beveled gears 117 at its respective ends, these gears meshing with the beveled gears 112 whereby simultaneous operation of the two screws 108 of the two ends of axle 103 is provided. A shaft 118 mounted in bearings 119 in frame 1, extends longitudinally of the car at one side thereof, and has worm wheels 120 mounted near its ends, which mesh with and drive the worm wheels 113 at the upper ends of the screws 108. The shaft 118 needs be provided on only one side of the car, and rotation of this shaft will through the gear connections already described, cause the simultaneous operation of all four of the lifting or lowering screws 108. A sprocket gear 121 secured to one end of shaft 118 is connected through sprocket chain 122 with a sprocket gear 123 which is free rotatable on the shaft 124 which extends longitudinally of the car in the upper central portion thereof. Obviously, any other suitable form of gear connections between shafts 118 and 124 could be substituted for the sprocket gearing here shown by way of example. Gear 123 is formed on its opposite ends with the clutch members 125 and 126. Cooperating clutch members 127 and 128 are keyed to the shaft 124 to rotate therewith, but are slideable along the shaft 124 into or out of engagement with the clutch members 125 and 126. The clutch members 126 and 128 are formed with engageable shoulders 129 and 130, connected by cam surfaces 131, whereby these clutch members will engage to drive the sprocket chain 122; when shaft 124 is rotated in the direction of the arrow, Fig. 7, but will automatically move out of engagement when the shaft 124 is rotated in the opposite direction. The clutch members 125 and 127 are provided with similar engaging shoulders and cam surfaces, but it will be noted that these clutch members are only adapted for operative engagement to drive the sprocket chain 122 in the opposite direction when shaft 124 is rotated in the direction opposite to the arrow in Fig. 7. A lever 132 controls the sliding movement of clutch member 128, and similarly a lever 133 moves the clutch member 127, the levers 132 and 133 being connected by a link 134 whereby when one clutch member is thrown into engagement the other is moved out of engagement and vice versa. The shaft 124 is driven from the shaft 50, described hereinabove, by sprocket connections indicated at 135.

With the frame 1 in its lowered position, as indicated in the drawings, shaft 124 will be driven in the direction indicated by the arrow, Fig. 2. The direction of rotation of shaft 124 may be changed as desired, by means of the reversing mechanism located at the engine or power plant 6. To raise the frame 1, the lever 132 is thrown over so as to cause the engagement of clutch members 126 and 128. Through the gear connections already described, the screws 108 will now all be simultaneously rotated so that they will screw up through the nuts 107 and raise the supporting frame above the axles 103 and wheels 2, the posts 105 sliding down through the guides 106. A stop mechanism is provided to prevent the excessive upward movement of the supporting frame. A rod 136 is secured at its lower end to one of the axles 103 (see Fig. 2), and the upper end of this rod slides through an opening 137 in a lever arm 138 extending laterally from the lower end of the clutch operating lever 132. A pair of nuts 139 and 140 are adjustably mounted on the threaded upper end portion of rod 136. As the supporting frame 1 and the mechanism carried thereby reach the desired upper limit of their travel, the lever arm 138 will come into engagement with the stop nut 139 and further upward movement will, through levers 138 and 132, withdraw the clutch member 128 from engagement with clutch member 126, thereby stopping the rotation of the several lifting screws 108. The clutch members will be left in the neutral position shown in Fig. 7. An excessive movement of lever 132 to the right in Fig. 7, thus bringing clutch member 127 into engagement with clutch member 125, would produce no results, since the cam surfaces on these two clutch members are so formed as to automatically throw them out of engagement when shaft 124 is rotating in the direction of the arrow, Fig. 7. With the supporting frame 1 in this raised position, the entire car can be transported to any location desired along the tracks 3 without danger of any portion of the mechanism encountering switch rails or crossings or other similar devices. In order to lower the frame and digging mechanism to their operative positions, as shown in the drawings, shaft 124 will first be rotated in the direction opposite to the arrow in Fig. 7 (by suitably manipulating the reversing mechanism at the engine 6), and then lever 132 will be thrown over to the right (Fig. 7), so as to bring clutch members 127 and 125 into operative engagement. This will cause the continued rotation of the gear connections in the directions opposite to that hereinabove described, and the screws 108 will be screwed down through the nuts 107, so as to lower the supporting frame. At the lower limit of this movement, the lever arm 138 will engage the stop nut 140 and throw the

clutches 127 and 125 out of engagement, thus stopping the screws in a manner similar to that first described. Although this mechanism has been described as adapted for raising the supporting frame from a standard lower position, where the diggers are normally operated, to a standard upper position for transportation from one locality to another, it is obvious that the same raising and lowering mechanism could be used for shorter vertical adjustments, to adjust vertically the operative range of movements of the diggers to meet special conditions.

An auxiliary set of supporting wheels 141 are suspended in brackets 142 extending downwardly from the supporting frame 1. These wheels 141 are positioned at right angles to the wheels 2 and normally will not be in engagement with anything but will simply hang freely from the lower portion of the supporting frame. When it is desired to remove the entire machine from the railway tracks 3, for example to store it at one side of the tracks and permit the passage of trains along the tracks, the lifting jacks are first operated as hereinabove described to raise the supporting frame and parts carried thereby to their upper positions. The auxiliary wheels 141 will now be raised to such a height above the tracks 3 that auxiliary tracks may be laid across these rails at right angles thereto and beneath the wheels 141. The lowering mechanism is now thrown into gear, whereupon the frame 1 will be lowered until the wheels 141 rest upon the auxiliary rails, and further rotation of the screws 108 in this direction will, through nuts 107, posts 105 and bearings 104, lift the axles 103 and wheels 2 clear of the rails 3, so that these parts will now be supported from the frame 1. The entire machine is now supported by the auxiliary wheels 141 and may be moved transversely from the trackway, along the auxiliary rails. Obviously the machine may be replaced upon the tracks 3 by reversing the steps hereinabove described.

I claim:

1. An apparatus for removing material from between the ties of a railway track comprising a supporting frame, digging mechanism mounted in the frame, power means for operating the digging mechanism also carried in the frame, wheels for movably supporting the frame on the track rails, a lifting jack interposed between each wheel and the frame, each jack comprising a vertical guide on the frame, a journal support for the wheel having a post slideable vertically in the guide, a nut in the post, a screw mounted in the frame and threaded in the nut, means comprising a plurality of countershafts and gears for simultaneously rotating the several screws, a shaft driven from the power means, driving connections be-

tween this shaft and one of the countershafts comprising clutch mechanism, and means for automatically throwing out the clutch mechanism when the frame reaches either the upper or lower limit of its movement.

2. An apparatus for removing material from between the ties of a railway track comprising a supporting frame, digging mechanism mounted in the frame, power means for operating the digging mechanism also carried in the frame, wheels for movably supporting the frame on the track rails, a lifting jack interposed between each wheel and the frame, each jack comprising a vertical guide on the frame, a journal support for the wheel having a post slideable vertically in the guide, a nut in the post, a screw mounted in the frame and threaded in the nut, means comprising a plurality of countershafts and gears for simultaneously rotating the several screws, a shaft driven from the power means, driving connections between this shaft and one of the countershafts including clutch mechanism, one member of which is slideable along said shaft into or out of clutching position, a lever for throwing this member in or out, and a rod connected at its lower end to a portion of the wheel supporting structure and having a stop projection which engages the lever to throw the clutch out when the frame reaches one limit of its vertical movement.

3. An apparatus for removing material from between the ties of a railway track comprising a supporting frame, digging mechanism mounted in the frame, power means for operating the digging mechanism also carried in the frame, wheels for movably supporting the frame on the track rails, a lifting jack interposed between each wheel and the frame, each jack comprising a vertical guide on the frame, a journal support for the wheel having a post slideable vertically in the guide, a nut in the post, a screw mounted in the frame and threaded in the nut, means comprising a plurality of countershafts and gears for simultaneously rotating the several screws, a drive shaft driven from the power means, driving connections between this shaft and one of the countershafts comprising a gear rotatable on the drive shaft, clutch members on opposite faces of this gear, cooperating clutch members keyed to the shaft and slideable into or out of engagement with the rotating clutch members, the engaging faces of the pairs of clutch members being so beveled that one set of clutches are adapted to drive the jacks only for raising same and the other set only for lowering same, lever connections for simultaneously sliding the keyed clutch members whereby only one can be in operative position at a time, and a rod connected at its lower end to the wheel supporting structure and having stop projections which engage

the lever connections to throw out the clutches when the frame reaches either the upper or lower limit of its travel.

4. An apparatus for removing material from between the ties of a railway track comprising a supporting frame, digging mechanism mounted in the frame, wheels for movably supporting the frame on the track rails, lifting jacks interposed between the wheels and frame, each jack comprising a rotatable member, gear connections for simultaneously rotating all of the rotatable members, a power means on the frame, a driving shaft driven from the power means, a gear rotatable on this driving shaft, this gear driving the gear connections to the rotatable jack members, there being clutch members on opposite faces of this driving gear, clutch members keyed to the driving shaft and slidable into or out of engagement with the respective clutch members on the driving gear, lever connections for simultaneously sliding the keyed clutch members whereby only one pair of clutch members can be moved into engagement at one time, a rod connected at its lower end to the wheel supporting structure, and adjustable stops on this rod for engaging the lever connections to throw the engaged clutches out of engagement when the frame reaches any desired point in its vertical travel.

5. An apparatus for removing material from between the ties of a railway track comprising a supporting frame, digging mechanism mounted in the frame, wheels for movably supporting the frame on the track rails, lifting jacks interposed between the wheels and frame, each jack comprising a rotatable member, gear connections for simultaneously rotating all of the rotatable members, a power means on the frame, a driving shaft driven from the power means, a gear rotatable on this driving shaft, this gear driving the gear connections to the rotatable jack members, there being clutch members on opposite faces of this driving gear, clutch members keyed to the driving shaft and slidable into or out of engagement with the respective clutch members on the driving gear, lever connections for simultaneously sliding the keyed clutch members whereby only one pair of clutch members can be moved into engagement at one time, and a rod connected at its lower end to the wheel supporting structure and having stop projections thereon which engage the lever connections to throw the engaged clutches out of engagement when the frame reaches the limit of its vertical travel in either direction.

6. An apparatus for removing material from between the ties of a railway track comprising a supporting frame, digging mechanism mounted in the frame, wheels for movably supporting the frame on the track rails, lifting jacks interposed between the wheels and frame, each jack comprising a rotatable member, gear connections for simultaneously rotating all of the rotatable

members, a power means on the frame, a driving shaft driven from the power means, a gear rotatable on this driving shaft, this gear driving the gear connections to the rotatable jack members, there being clutch members on opposite faces of this driving gear, clutch members keyed to the driving shaft and slidable into or out of engagement with the respective clutch members on the driving gear, lever connections for simultaneously sliding the keyed clutch members whereby only one pair of clutch members can be moved into engagement at one time, a rod connected at its lower end to the wheel supporting structure, and adjustable stops on this rod for engaging the lever connections to throw the engaged clutches out of engagement when the frame reaches any desired point in its vertical travel.

7. In an apparatus for removing the material from between the ties of a railway track, a supporting structure, a digger, means for supporting and operating the digger in the space between a pair of ties, means for lowering the supporting means and digger as the material is removed, and means for shifting the digger laterally with relation to its supporting means as it is lowered to bring its path of operation beneath the rail, said latter means comprising a member pivotally supported at its upper end and adapted to swing at its lower end longitudinally of the ties, the lower portion of this member embodying cam slots engaged by portions of the digger and supporting means respectively.

8. In an apparatus for removing the material from between the ties of a railway track, a supporting structure, a digger, means for supporting and operating the digger in the space between a pair of ties, means for lowering the supporting means and digger as the material is removed, and means for shifting the digger laterally with relation to its supporting means as it is lowered to bring its path of operation beneath the rail, said latter means comprising a member pivotally supported at its upper end and adapted to swing at its lower end longitudinally of the ties, the lower end of this member being formed with a pair of substantially vertically extending cam slots, the lower ends of the slots slanting toward one another, a projection on the digger engaging in one slot, and a projection on the digger-supporting means engaging in the other slot.

9. In an apparatus for removing the material from between the ties of a railway track, a supporting structure, a digger, means for supporting and operating the digger in the space between a pair of ties, means for lowering the supporting means and digger as the material is removed, and means for shifting the digger laterally with

relation to its supporting means as it is lowered to bring its path of operation beneath the rail, said latter means comprising a member pivotally supported at its upper 5 end and adapted to swing at its lower end longitudinally of the ties, the lower end of this member being formed with a pair of substantially vertically extending cam slots, the lower portion of one of these slots inclining inwardly toward the rail, the lower portion of the other slot inclining outwardly toward the first slot, a projection on the digger engaging in the first named slot, and a projection on the digger-supporting means 10 engaging in the second slot.

10. In an apparatus for removing the material from between the ties of a railway track, a supporting structure, a digger, means for supporting and operating the digger in the space between a pair of ties, means for lowering the supporting means and digger as the material is removed, and means for shifting the digger laterally with relation to its supporting means as it is lowered to bring its path of operation beneath the rail, said latter means comprising a member pivotally supported at its upper end, means for causing the lower portion of this member to swing with the digger operating mechanism, a cam slot in the member which inclines inwardly toward the rail, and a projection on the digger engaging in this slot.

11. In an apparatus for removing the material from between the ties of a railway track, a supporting structure, a digger, means for supporting and operating the digger in the space between a pair of ties, means for lowering the supporting means and digger as the material is removed, and means for shifting the digger laterally with relation to its supporting means as it is lowered to bring its path of operation beneath the rail, said latter means comprising a member pivotally supported at its upper end, means for causing the lower portion of this member to swing with the digger operating mechanism, a cam slot in the member having a substantially vertical upper portion and an inwardly inclined lower portion, and a projection on the digger engaging and sliding in this slot as the digger is raised or lowered.

12. An apparatus for removing material from between the ties of a railway track, comprising a supporting frame, a rotary crank mounted in the frame, means for rotating the crank, a pair of swinging frames pivotally suspended in spaced relation in the upper portion of the frame, means for simultaneously raising or lowering the frames, a pitman pivoted at one end to the crank and intermediately to one of the swinging frames, a lever pivoted at one end to the other swinging frame and intermediately

ately to the pitman, a carriage suspended from the remaining ends of the lever and pitman, guides on the carriage, a digger slideable along the guides longitudinally of the ties, and means for adjusting the digger 70 along the guides as the carriage and digger are raised or lowered, said means comprising a member pivotally supported at its upper end and formed with cam slots in its lower portion engaged by portions of the 75 digger and the carriage supporting mechanism respectively.

13. An apparatus for removing material from between the ties of a railway track, comprising a supporting frame, a rotary 80 crank mounted in the frame, means for rotating the crank, a pair of swinging frames pivotally suspended in spaced relation in the upper portion of the frame, means for simultaneously raising or lowering the 85 frames, a pitman pivoted at one end to the crank and intermediately to one of the swinging frames, a lever pivoted at one end to the other swinging frame and intermediately to the pitman, a carriage suspended from the remaining ends of the lever and pitman, guides on the carriage, a digger slideable along the guides longitudinally of the ties, and means for adjusting the digger 90 along the guides as the carriage and digger are raised or lowered, said means comprising a member pivotally supported at its upper end and formed in its lower portion 95 with a pair of substantially vertically extending cam slots, the lower portion of one slot inclining inwardly toward the rail, and the lower portion of the other slot inclining outwardly toward the first slot, a bracket extension on the digger engaging in the first named slot, and one of the pivotal connections of the carriage supporting means 100 engaging in the second slot.

14. In an apparatus for removing the material from between the ties of a railway track, a supporting structure, a digger, 110 means for supporting and operating the digger in the space between a pair of ties, means for lowering the supporting means and digger as the material is removed, and means for shifting the digger laterally with 115 relation to its supporting means as it is lowered to bring its path of operation beneath the rail, said latter means comprising a member pivotally supported at its upper end and adapted to swing at its lower end 120 longitudinally of the ties, the lower portion of this member embodying cam slots engaged by portions of the digger and supporting means respectively, and means for raising this pivoted member as the digger 125 is lowered, or vice versa.

15. In an apparatus for removing the material from between the ties of a railway track, a supporting structure, a digger, means for supporting and operating the 130

digger in the space between a pair of ties, means for lowering the supporting means and digger as the material is removed, and means for shifting the digger laterally with 5 relation to its supporting means as it is lowered to bring its path of operation beneath the rail, said latter means comprising a member pivotally supported at its upper end and adapted to swing at its lower end longitudinally of the ties, the lower end of this member being formed with a pair of substantially vertically extending cam slots, the lower portion 10 of one of these slots inclining inwardly toward the rail, the lower portion of the other slots inclining outwardly toward the first slot, a projection on the digger engaging in the first named slot, and a projection on the digger-supporting means engaging in the second slot, and means for raising this 15 pivoted member as the digger is lowered, or vice versa.

16. In an apparatus for removing material from between the ties of a railway track, a supporting frame, a set of levers intermediately pivoted in the upper portion of the supporting frame, a pair of swinging frames pivotally suspended from similar arms of the levers, a carriage suspended from the swinging frames, means for swinging the frames 20 and carriage, guides on the carriage, a digger 25 slideable along the guides longitudinally of the ties, and means for moving the digger along the guides as the carriage and digger are raised and lowered, said means comprising 30 a member pivotally suspended from other arms of the first-named levers so that it will be raised as the digger is lowered and formed with cam slots in its lower portion 35 engaged by portions of the digger and carriage supporting mechanism respectively.

17. An apparatus for removing material from between the ties of a railway track, comprising a supporting frame, a rotary crank mounted in the frame, means for 45 rotating the crank, a set of intermediately pivoted levers mounted in the upper portion of the supporting frame, a pair of swinging frames pivotally suspended in spaced relation from similar arms of the levers, means 50 for swinging the levers in unison to raise or lower the frames, a pitman pivoted at one end to the crank and intermediately to one

of the swinging frames, a lever pivoted at one end to the other swinging frame and intermediately to the pitman, a carriage suspended from the remaining ends of the lever and pitman, guides on the carriage, a digger 55 slideable along the guides longitudinally of the ties, and means for adjusting the digger along the guides as the carriage and digger 60 are raised or lowered, said means comprising a member pivotally supported at its upper end from one of the first-named levers so that it will be raised as the digger is lowered and formed with cam slots in its lower portion 65 engaged by portions of the digger and the carriage supporting mechanism respectively.

18. In an apparatus for removing material from between the ties of a railway track, 70 comprising a supporting frame, a rotary crank mounted in the frame, means for rotating the crank, a set of intermediately pivoted levers mounted in the upper portion of the supporting frame, a pair of swinging 75 frames pivotally suspended in spaced relation from similar arms of the levers, means for swinging the levers in unison to raise or lower the frames, a pitman pivoted at one end to the crank and intermediately to one 80 of the swinging frames, a lever pivoted at one end to the other swinging frame and intermediately to the pitman, a carriage suspended from the remaining ends of the lever and pitman, guides on the carriage, a digger 85 slideable along the guides longitudinally of the ties, and means for adjusting the digger along the guides as the carriage and digger are raised or lowered, said means comprising a member pivotally supported at its 90 upper end from one of the first-named levers so that it will be raised as the digger is lowered and formed in its lower portion with a pair of substantially vertically extending cam slots, the lower portion of one 95 slot inclining inwardly toward the rail, and the lower portion of the other slot inclining outwardly toward the first slot, a bracket extension on the digger engaging in the first named slot, and one of the pivotal connections of the carriage supporting means 100 engaging in the second slot.

EMMONS OVERMIER.
